UNITED STATES PATENT OFFICE.

HAROLD McCREADY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

CIRCUIT-CONTROLLER.

1,071,769.

Specification of Letters Patent.

Patented Sept. 2, 1913.

Application filed March 29, 1911. Serial No. 617,749.

To all whom it may concern:

Be it known that I, HAROLD McCREADY, a citizen of the United States, residing at Wilkinsburg, in the county of Allegheny 5 and State of Pennsylvania, have invented certain new and useful Improvements in Circuit-Controllers, of which the following is a specification.

My invention relates to circuit controllers, 10 and particularly to the contacts and means for operating the contacts comprised in circuit controllers.

I will describe a circuit controller embodying two forms of my invention, and then 15 point out the novel features thereof in claims.

In the accompanying drawings, Figure 1 is a view showing in elevation a circuit controller embodying my invention. Fig. 2 is 20 a bottom plan view of the circuit controller shown in Fig. 1. Fig. 3 is a view showing in side elevation the lower portion of the circuit controller shown in Fig. 1. Fig. 4 is a view showing a portion of the circuit controller shown in the preceding views, but 25 with the parts in different relative positions. Fig. 5 is a view showing on a larger scale a portion of the circuit controller shown in Figs. 1, 2 and 3.

30 Similar reference characters refer to similar parts throughout the several views.

In circuit controllers or "relays" employed for certain purposes, for example, in those employed for the control of railway 35 signals, it is frequently desirable to provide contacts having low electrical resistance between the contacting members when in engagement. This may be readily effected by the use of contacts the members of which 40 are of substantially metallic material, such for example as a platinum or a silver member, and a silver member, adapted to be moved into and out of engagement with each other. But a contact of such nature 45 is subject to the danger of the two members becoming fused together under abnormal conditions, such as by lightning discharges. One feature of my invention is the operation 50 of one or more contacts of low resistance (such as those comprising substantially metallic members only) and one or more non-fusible contacts (such as those of which one member is carbon or a similar material) by one contact operating member, the arrangement being such that if the members 55 of the low resistance contact should become

fused together while in engagement, the contact operating member is still free to move the members of the high resistance contact out of engagement, independently of the low resistance contact. In practice, the contact 60 operating member is usually an armature controlled by a motor of a suitable nature, such as by an electro-magnet, although I do not wish to limit myself to contacts operated 65 by any particular means.

Referring to Figs. 1, 2 and 3 of the drawings, 10 designates a supporting base, preferably of insulating material such as porcelain, in which is mounted an electro-magnet 70 11. This electro-magnet comprises as usual two energizing windings 13, 13, and two pole pieces 15 and 16, and it controls a "neutral" armature 12 and a "polarized" armature 14. As is well understood, the neutral 75 armature 12 is "closed" or attracted to the pole pieces 15 and 16 when the windings 13 are energized by current flowing in either direction, whereas the polarized armature 14 is rocked to engagement with one pole 80 piece or the other depending on the direction of flow of current in the windings 13. A circuit controller such as I have thus far described is well known, and requires no further explanation. As here shown, the 85 neutral armature 12 operates two contacts 75 and 76, of which contact 75 comprises two metallic members 22 and 23, and contact 76 comprises a metallic member 19 and a carbon member 20. The polarized armature 90 operates two contacts 77 and 78, of which contact 77 comprises two metallic members 35 and 37, and contact 78 comprises a metallic member 34 and a carbon member 36. The neutral armature 12 carries two 95 studs 17, 17, preferably of a suitable insulating material, to which studs is secured a contact finger 18. This contact finger carries at its outer end the metallic contact member 19 forming part of contact 76. The 100 carbon member 20 of this contact is a stationary block suitably supported in the base 10.

21 designates another contact finger pivoted to a support 24 which support is suitably mounted in the base 10. This finger 105 21 carries at its outer end the metallic member 22 forming part of the contact 75. The other metallic member 23 of this contact is a stationary block suitably supported in the 110 base 10. The contact finger 21 is operatively connected with the armature 12 by means of

a stud 25. As shown more clearly in Fig. 5, this stud comprises means whereby it may be secured to the armature 12, here shown as being a threaded portion 79. It also has 5 a reduced portion or neck 26 and a head 27. The head 27 is preferably substantially rectangular in shape, its narrower dimension being substantially equal to the diameter of the neck 26. The contact finger 21 is provided with a slot 28 which fits loosely over the neck 26. The head 27 of the stud 25 may be passed through this slot, and the stud being then turned through an angle of 90 deg., the contact finger 21 is then 10 constrained to movement within the limits of the neck 26. The proportions of the stud 25 are such that during the closing of the armature 12 against the pole pieces 15 and 16, the head 27 of the stud will engage 15 the contact finger 21 to move the contact member 22 into engagement with the block 23; and if these two contacts should become fused together in this position, the armature 12 will, upon being released, move 20 to its lower position, carrying with it the contact finger 18, thereby opening contact 76. In other words, the length of the neck 26 of the stud 25 is such that the armature 12 may move freely through its entire stroke 25 even if the contact member 22 should become fused to the contact block 23.

Referring now particularly to Figs. 2 and 4, I will explain one form of apparatus for operating the contacts 77 and 78 by the 30 polarized armature 14. 29 and 30 designate respectively two pairs of studs of suitable insulating material rigidly secured to the armature 14. Secured to the studs 29 is a contact finger 31 carrying at its outer end 35 the metallic member 34 of the contact 78. The carbon member 36 of this contact is a block suitably mounted in the base 10. The studs 30 carry a finger 32, to which a second finger 33 is so secured that the latter may 40 be easily bent outwardly with respect to the finger 32. As here shown, the finger 33 is secured to the finger 32 by means of rivets 38. The finger 33 carries at its outer end one of the metallic members 35 of the 45 contact 77. The other metallic member 37 of this contact is a block suitably mounted in the base 10. The two contacts 77 and 78 here shown are so arranged that they 50 will both be closed when the armature 14 is rocked in one direction, and that they will both be opened when the armature is rocked in the other direction. The movement of the finger 33 with respect to the finger 32 55 is such that if the two metallic members of contact 77 should become fused, the armature 14 would still be free to be rocked to its other extreme position, thereby opening contact 78. In such case, the fingers 32 and

33 would assume substantially the relative positions shown in Fig. 4.

Although I have herein shown and described only one form of circuit controller having two forms of contacts embodying my invention, it is understood that various changes and modifications may be made 70 therein within the scope of the appended claims without departing from the spirit and scope of my invention.

Having thus described my invention, what I claim is:

1. In a circuit controller, an electro-magnet, an armature controlled thereby, two contact fingers, one of which is rigidly secured to the armature and the other of which is pivoted to have movements relatively to the armature, a stud secured to the armature and having a body portion and an enlarged head portion, and a hole in the pivoted contact finger which will pass freely over the body portion of the stud but which 85 will not pass over the head portion.

2. A circuit controller comprising a movable contact operating member, a fusible contact and a non-fusible contact, each contact comprising a stationary member and a movable member, the movable member of the non-fusible contact being connected with the operating member to be positively moved thereby during movement of the operating member in both directions, and means interposed between the operating member and the movable member of the fusible contact for closing the latter when the operating member moves in such direction as to close the non-fusible contact and 95 for permitting return movement of the operating member to open the non-fusible contact independently of the movable member of the fusible contact in case the latter should become fused while closed.

3. A circuit controller comprising a movable operating member, a non-fusible contact connected with the operating member to be positively moved thereby during movements of the latter in both directions, 100 a fusible contact, and means interposed between the operating member and the fusible contact for closing the latter when the operating member moves in such direction as to close the non-fusible contact and for permitting return movement of the operating member to open the non-fusible contact independently of the fusible contact in case the latter should become fused while closed.

In testimony whereof I affix my signature 120 in presence of two witnesses.

HAROLD McCREADY.
